UNITED STATES PATENT OFFICE

FRANK LAWRENCE FRY, OF MARSHALLTOWN, IOWA

ADJUSTABLE GUIDE FOR SLIDING DOORS

Application filed February 3, 1930. Serial No. 425,466.

The object of this invention is to provide an improved guide for sliding doors which is adjustable to compensate for variations in the thickness or position of the door.

- 5 A further object of the invention is to provide an improved adjustable guide for a sliding door in which a curved member is held in position by a wedge-shaped locking piece in such manner that the door may be firmly gripped and held irrespective of variations in the thickness or position of the outer surface of the door due to changes caused by atmospheric conditions, presence of moisture, or other causes.
- 10 Another object is to provide an arrangement of parts whereby a box car door may be moved easily and freely when desired, without the use of tools, thus avoiding damage to parts which are ordinarily broken in forcing the door, and at the same time permitting the door to be held securely and tightly in place when closed.

With these and other objects in view, my invention consists in the construction, arrangement and combination of elements set forth, pointed out in my claims, and illustrated in the accompanying drawings, in which:

Figure 1 is a perspective view illustrating the various parts of my improved guide prior to assembly.

Figure 2 is a horizontal section through a portion of a railway car equipped with two of my improved adjustable guides and with other guides of the old rigid type.

Figure 3 is a vertical section through one of the adjustable guides substantially on line 3—3 of Figure 2.

Figure 4 is a vertical section through one of the guides and a portion of a door engaged thereby, taken substantially on line 4—4 of Figure 3.

My improved guide is particularly designed for use in connection with the sliding doors of railway freight cars which are exposed to the weather and to greatly varying atmospheric and moisture conditions, and are frequently the cause of considerable trouble and annoyance in operation.

50 In the drawings I have illustrated a por-

tion of a wall 10 of a railway car having a door opening 12 adapted to be closed by a door 14 suspended at its top from a track not shown. In Figure 2 I have shown the wall 10 as being equipped with three guides of the old or rigid type, each of said guides including a bracket 16 and a curved guide member 18 rigidly carried thereby and adapted to engage the lower marginal portion of the door 14. It is obvious that unless the curved guide member 18 is so arranged as to contact quite closely with the outer surface of the door, the door will be capable of considerable swinging movement.

It is also to be noted that if the guides are so arranged as to fit snugly to the door under normal conditions, that considerable trouble may be experienced in case the door 14 should warp or swell on account of excessive moisture. To overcome this difficulty, I have provided my adjustable guides which may be used either alone or in connection with the old type as shown.

The adjustable guide includes a bracket having a base portion 20 which forms an inner guide for the door. The base portion 20 is formed with apertures 22 to receive bolts or other suitable fastening means by which the bracket may be mounted on the wall 10. The base member 20 may also be formed at its lower margin with a downwardly opening slot 24 to receive a bolt 26 or other fastening member. As here shown, the slotted portion of the base 20 is covered by a downwardly opening hood 28 which covers the head of the bolt 26 and adds strength to the structure.

The base 20 is formed with a pair of outwardly projecting parallel ears 30 and 32 and these ears are formed respectively with horizontally arranged elongated slot openings 34 and 36. The ears 30 and 32 are spaced somewhat from the upper margin of the base portion 20 and preferably are joined at the lower margins to the top of the hood 28.

An outer guide member 38 is separately formed and this guide member is concavo-convex in cross section and is similar to the guide member 18 of the old type of guide bracket.

100

The guide member 38 is formed with a centrally arranged lug 40 projecting radially from its convex surface and adapted to be received between the spaced ears 30 and 32.

5 The lug 40 is formed with a slot opening 42 adapted to register with the openings 34 and 36.

A wedge-shaped securing member 44 is provided and is adapted to be inserted through 10 the slots 36, 42, and 34 for the purpose of adjustably holding the outer guide member 38 in place. It will be noted that the securing member 44 is relatively narrow at its initial end and is widened in a horizontal plane toward the other end which preferably terminates in an enlargement or head 46.

The parts of the device are assembled by inserting the lug 40 of the outer guide member between the ears 30 and 32, and then placing the wedge-shaped securing member 44 in position by extending it through the slots 36, 42, and 34. Means preferably is provided for preventing a complete withdrawal of the securing member 44 and such means 25 may constitute a rivet or the like 48 extending through the aperture 50 in the smaller end of the member 44. The member 48, of course, is placed in position after the securing member 44 has been mounted in place.

30 It is obvious that the spacing of the convex surface of the outer guide member 38 from the base portion or inner guide member 20 will be determined by the position of the wedge-shaped securing member 44. In 35 other words, the member 44 may be adjusted longitudinally in the slots to adjust the lateral capacity of the guide.

When it is desired to move the door 14 on its track, the wedge-shaped securing members 44 of the adjustable guides may be loosened, thus permitting free and easy travel of the door within said guides. When the door is in the desired position, the adjustable guides may be tightened by driving the 45 wedge-shaped securing members 44 home with a hammer or similar tool and the wedging action will cause the convex surfaces of the curved guide members 38 to tightly engage the outer surface of the door and thus 50 prevent any undesirable swinging or oscillation.

It may be convenient to use on a given installation several of the old type of rigid guides and these guides may be of sufficient 55 lateral width to permit free passage of the door 14 under all conditions which may be encountered. To supplement the rigid guides, it may be found desirable to use one or more of the adjustable guides for engaging 60 the door when in closed position and one or more for engaging the door when in open position. This arrangement will permit free travel of the door at all times and under all 65 conditions upon loosening the wedge-shaped securing members 44 and will also permit the

door to be firmly held in either of its positions by tightening up said wedge members when the door has been set in its place.

The head 46 and the retaining member 48 of the wedge-shaped securing member serve 70 to prevent complete withdrawal of said member and thus prevent the possibility of misplacing or losing it.

Some changes may be made in the arrangement and construction of the various parts of my adjustable guide for sliding doors without departing from the real spirit and purpose of my invention, and it is my intention to cover by my claims, any modified forms 75 of structure or use of mechanical equivalents, so which may be reasonably included within their scope.

I claim as my invention:

1. An adjustable guide for sliding doors, comprising a base portion adapted to be secured to a wall, a pair of spaced slotted ears projecting from said base portion, an outer guide member formed with a laterally projecting lug adapted to be received between said ears and having a slot arranged to register with the slots thereof, and a wedge-shaped securing member slidably mounted in the slots of said ears and lug for adjusting the spacing of said guide member relative to the base. 90

2. An adjustable guide for sliding doors, comprising a base portion adapted to be secured to a wall, a pair of spaced slotted ears projecting from said base portion, an outer guide member formed with a laterally projecting lug adapted to be received between said ears and having a slot arranged to register with the slots thereof, and a wedge-shaped securing member slidably mounted in the slots of said ears and lug for adjusting the spacing of said guide member relative to the base, together with means to prevent complete withdrawal of said securing member from said slots. 100

3. An adjustable guide for sliding doors, comprising a base having a flat portion forming an inner guide, a pair of spaced parallel ears projecting laterally from said base and formed with registering slots, an outer guide member having a convex face, a lug projecting laterally from the convex face of said guide member and adapted to be received between said ears, said lug being formed with a slot adapted to register with the slots of said ears, and a wedge-shaped securing member slidably mounted through the slots of said ears and lug for adjustably holding the outer guide member relative to the base. 110
